MACHINE FOR FORCING FITTINGS INTO
THE ENDS OF WOODEN BARS

Hans K. Lorentzen, Montclair, N. J., assignor to
Lorentzen Hardware Mfg. Corp., New York,
N. Y., a corporation of New York

Application April 22, 1939, Serial No. 269,405

13 Claims. (Cl. 1—1)

This invention relates to improvements in machines for forcing fittings into the ends of wooden members, and more particularly to machines for forcing fittings into the ends of wooden Venetian blind bars.

In the manufacture of Venetian blinds, it is desirable to insert fittings of various characters into the ends of certain of the bars used in the blind and heretofore such insertion has been accomplished with considerable difficulty. This is particularly true in the case of wood which splits readily, such as yellow pine, for the reason that the insertion of fittings into the ends of bars made of this wood has been accomplished only by first drilling or otherwise removing some of the material of the bar prior to the insertion of the fitting. If efforts are made to force a fitting into the bar without such prior removal of some of the material thereof, this operation has resulted almost uniformly in splitting the bar.

An object of the present invention is to provide a machine which can be utilized for forcing fittings into the ends of wooden bars without causing or permitting splitting of the bar.

Another object of the invention is to provide a machine of such character that a bar is held against movement and also against splitting in the usual direction during the forcing of a fitting into the end thereof.

Another object of the invention is to provide a machine of the foregoing character in which the forcing element is interchangeable to accommodate fittings of various characters.

Another object of the invention is to provide a machine of the foregoing character in which provision is made for accommodating bars of the various widths customarily used in Venetian blinds.

Another object of the invention is the provision in the machine of means for accommodating therein bars of various thickness such as are customarily used in Venetian blind structures.

A further object of the invention is to provide clamping means for holding a bar, which clamping means is manually operated with the operating member or mechanism being adjustable to fit the individual operator.

A further object of the invention is to provide, in conjunction with forcing members for fittings, guide means and fitting retention means for keeping a fitting in alignment during the initial stages of the forcing operation.

In carrying out the foregoing and other objects of the invention, a machine embodying the fea-

tures of this invention is made up of a base to which is secured a bar clamping device. The device in brief comprises a vertically movable plate which can be moved into bar clamping position by means of a rotatable cam acting on the top of the plate. In conjunction with the clamping means, use is made of bar aligning mechanism comprising a stop for one end of the bar and slideable guide members for aligning the edges of the bar with the stop. Associated with the stop is a guideway both for fittings and for forcing members, which latter members are slideable in the guideway and which are adapted to force a fitting into the end of a wooden bar held by the clamping mechanism. Since fittings of various characters are ordinarily forced into a bar as occasion may demand, the present invention provides an arrangement wherein various forcing members can be interchanged to make possible the adaptation of the machine to the particular fittings. The forcing member may be operated in any suitable fashion such as by a foot treadle or any other desired mechanism.

Since Venetian blinds are made up in various sizes it follows that bars of different thicknesses and of different widths must of necessity be processed by this machine. Accordingly, provision is made in the clamping mechanism for clamping bars of different thicknesses therein in proper alignment with the fitting guide so that a fitting can be forced into the bar midway between the upper and lower edges thereof. Provision is also made for aligning bars of different widths with the clamping mechanism and with the fitting guideway, such means comprising in a part a support for the opposite end of the bar with adjustable side aligning members.

Other features, objects and advantages of the invention will become apparent by reference to the following detailed description of the accompanying drawings wherein

Fig. 1 is a plan view of a machine embodying the invention;

Fig. 2 is a section taken substantially on the line 2—2 of Fig. 1;

Referring now to the drawings, and particularly to Figs. 1 and 2, 10 indicates the metallic base of the machine upon which the operating elements are mounted. These elements comprise clamping mechanism indicated generally at 11 and fitting forcing mechanism indicated generally at 12.

The clamping mechanism is made up of two angle members 14 having upstanding plate-like parts 15. These upstanding parts 15 are spaced apart a suitable distance, the members 14 being secured to the base 10 in any suitable manner. Located between the upright members 15 is a clamping plate 16, which plate 16 has oppositely disposed ears 17 extending through suitable openings 18 in the uprights 15. The openings 18 extend upwardly an amount sufficient to permit the plate 16 to be raised to the desired upper limits. Coiled springs 19 are positioned between the under surfaces of the ears 17 and the top surface of the angle members 14 to elevate the plate 16.

In order that the clamping plate 16 may be forced downwardly against the resistance of springs 19, use is made of a cam 20 secured on a shaft 21 which is rotatably mounted in bearing openings formed in the uprights 15. The uprights 15 have enlargements or bosses 22 for the purpose of providing longer bearing surfaces. As shown in Figs. 1 and 3, the cam 20 is disposed substantially mid way between the uprights 15, such disposition being accomplished by a spacer collar 24 at one side of the cam and an integral extension 25 on the other side of the cam, which extension is provided with a plurality of surfaces in the nature of engaging surfaces. In the form illustrated, these surfaces are six in number. Also as a part of the integral extension 25 and the cam 20 is a collar portion 26 which serves to complete the spacing means between one side of the cam and one upright 15. This collar 26

has a set pin 27 extending therethrough into contact with the shaft 21 to lock the cam to the shaft.

To accomplish rotation of the shaft, a handle or lever 28 is provided. This handle 28 has one end part thereof formed of an enlargement hollowed out and provided with a plurality of corrugations of such shape as to closely correspond to the shape of a box socket type wrench. The purpose of these corrugations 28 is to permit adjustment of the handle relative to any desired part of the cam surface. The socket part of the handle is of a thickness corresponding substantially to the length of the part 25 of the integral extension of the cam and the corrugations 28 are of such dimensions and of such number that this handle can be adjusted to any desired position relative to the cam by simply moving the handle until the socket part thereof is out of engagement with the wrench engaging surfaces 25, turning the handle to the desired position and then engaging the socket portion with the surfaces 25. To prevent the handle from becoming adventitiously disengaged from the wrench engaging surfaces 25, use is made of a keeper member 30 in the nature of a plate pivoted on a shaft 31 extending through the uprights 15 and held in place by cotter pins 32 or by any other suitable arrangement. The keeper member 30 has a part thereof cut out as indicated at 34, which cutout part is dimensioned to fit snugly partially around the collar part 26 of the cam element. When this keeper is in the position shown in Fig. 2, it serves to prevent the handle from being moved longitudinally of the cam element to disengage the handle from the surfaces 25. The shaft 31 also serves the purpose of a stop for the handle in one extreme position thereof. The handle 28 as shown in Fig. 3 may be of any desired length, but its effective length may be increased by telescopically fitting an extension member 135 onto one end of the handle. The member 135 as shown can be of tubular form. Provision is made for fastening the extension 135 to the handle 28 and as shown in the drawings, this arrangement comprises a button-like member 136 seated partially in a recess 137 in member 28. In addition to the button 136, use is made of a spring 138 likewise positioned in the same recess. The button has a flange part as shown so that when the spring and the flange part have been inserted into the recess, the material of the handle can be spun over the flange to retain it in the recess. The extension 135 has an aperture 139 in the wall thereof to receive the outer end of the button 136.

Fastened to one edge of the base 10 and extending longitudinally therefrom is an angle bar 35 which has a cross-bar 36 fastened to the extreme end thereof. The top surface of the bar 36 is substantially in the same plane as the surface of the base 10 between the uprights 15. This bar 36 serves as a support for one end of a wooden bar 37 which can be held by the clamping mechanism. Bar 37 is of the type commonly used in Venetian blind constructions and particularly of a type used as a tilt bar for such structures. Since tilt bars conventionally used in this art may be of any one of various widths, provision is made for obtaining proper alignment of at least three widths of bars in this clamping mechanism. As shown in Fig. 1, the cross-bar 36 has three openings 38 therein in diagonal relation across the bar. A pin 39 has a portion of reduced diameter 43 to fit in any one of the

three openings 38 with the major portion 39 extending upwardly from the bar 37. These openings 38 are so positioned that when the pin 39 is in the proper opening, as indicated by the legendary matter (Fig. 1), a wooden bar 37 of the proper width corresponding to the position of pin 39 will be partially aligned with the clamping mechanism. The number of openings 38 may be increased in accordance with the number of widths of wooden bars to be processed.

In addition to the aligning devices just described, use is made of further aligning mechanism positioned to operate upon the other end of the wooden bar 37. This latter mechanism comprises in part a stop 40 secured to the base 10 in any suitable manner together with a sliding member 41 which is of generally U-shape. The sliding member 41 is made of flat metal and is positioned upon the upper surface of the base 10. Since this member is as before stated of general U-shape, it follows that the stop 40 is positioned between the legs of the member 41. This member 41 is retained on the base by means of overlying plates 42 resting on spacing members 44 slightly thicker than the member 41. The plates 42 and the spacers 44 can be secured to the base by screws passing through them into the base or in any other suitable manner. Extending upwardly from the member 41 are a pair of posts 45 and extending upwardly from the opposite plates 42 are posts 46. Springs 47 are secured between posts 45 and 46 as shown in Fig. 1. The ends of the U-shaped member 41 are tapered inwardly and are provided with upstanding flanges 48.

The member 41 cooperates with the end of the stop member 40 and with the properly located pin 39 to align a bar 37 in the machine. Normally the member 41 is in a position in which the inner ends of the flanges 48 extend beyond the end of the stop member 40 toward the clamping mechanism, which position is due to the action of the springs 47. When it is desired to align a bar 37 in a machine, the end thereof, in which a fitting is to be forced, is inserted under the clamping plate 16 and the bar is moved until the ends thereof engage the surfaces of the flanges 48. The other end of the bar 37 has one side thereof resting against the pin 39 positioned in the proper opening 38 dependent upon the width of the bar 37. This bar 37 can then be moved toward the stop 40 until the end of the bar contacts this stop, during which movement the member 41 is moved against the action of the springs 47. The cooperation of the various parts in this manner assures that the bar 37 will be properly aligned in the machine so that a fitting can be forced into the end of the bar with the side edges of the fitting symmetrically located relative to the side edges of the wooden bar. When the bar has been so properly positioned, it can be clamped in place by manipulation of the handle 28 in such manner that the cam 20 forces the clamping plate 16 downwardly into contact with the top surface of the bar 37. The desired amount of clamping pressure can be applied through the handle 28 to force the clamping plate 16 into such contact with the wooden bar as to firmly hold it in place and as to effectively resist cross splitting of the bar upon the introduction of a fitting thereinto.

The forcing of a fitting into the end of the wooden bar is accomplished by the following mechanism. The member 40 previously de-

scribed as having one function of serving as a stop for the end of a wooden bar also has other functions such as providing a guideway for a fitting and also a guideway for a piston member used in forcing the fitting into the wooden bar. For these latter functions, the top surface of the member 40 has an acute shaped depression 50 midway between the side edges thereof and extending rearwardly a suitable distance from one end of the member. In addition, surfaces 51 are provided in the top of the member 40 on each side of the depression 50 and below the top surface of the member 40. These surfaces extend the full length of the member 40. The rear half of the member 40 is of greater height than the front half thereof and a plate 52 is secured across the top of this rear part, thereby providing a channel of substantially rectangular shape in cross-section. The floor of this channel is formed in part by the two surfaces 51. This channel serves as a guideway for a piston 55 which is of similar shape in cross-section, i. e. substantially rectangular. The piston slides in the guideway so formed and upon the surfaces 51. The rear end of the piston 55 fits in a forked end of a sliding member 56, which member passes through bosses 57 extending upwardly from the base 10. The piston 55 has a through opening 58 therein which can be brought into register with aligned openings 59 in the forked front end of the member 56 and a pin 60 can pass through the aligned openings 58 and 59 to secure the piston to the member 56. The rear end of the member 56 is vertically forked as indicated at 63 to receive a rounded end 61 of a bell crank 62. A pin 64 is secured through the forked end of the member 56 to retain the end 61 of the crank in the fork of this member 56. The bell crank 62 is pivotally mounted between two members 65 depending from the under side of the base 10 and this base 10 is slotted for the passage of one arm of the bell crank 62. The other end of the bell crank 62 has secured thereto a bar 66 which can be connected to a suitable treadle (not shown) so that pressure applied by an operator's foot will serve to rotate the crank about its pivotal point and thereby move the member 56 and associated piston 55 toward the clamping mechanism. A spring 67 can be connected between the bar 66 and a hook 68, secured to the base 10, to move the bell crank in the opposite direction and due to the engagement of the head 61 of the crank with the pin 64, such movement of the crank under the impetus of spring 67, moves the member 56 and associated piston 55 away from the clamping mechanism.

The piston shown in Figs. 1 to 6 inclusive is designed for use in forcing a fitting of the Fig. 8 type into one end of a wooden bar. By reference to Fig. 8, it will be seen that this fitting is a substantially flat member of generally U-shape and having the legs thereof provided with inwardly extending teeth 70. This fitting can be stamped from sheet metal or formed in any other suitable fashion. The width of the fitting is substantially equal to the width of the guideway formed by the surfaces 51 so that this fitting can be positioned on these surfaces in the manner shown clearly in Figs. 1 and 6.

The forward end of the piston 55 has its under surface cut away as at 71 an amount substantially equal to the thickness of the Fig. 8 fitting. Due to this arrangement, it is possible to locate a Fig. 8 fitting in the guideway with the rear end of the fitting lying under the for-

ward end of the piston 55. This piston 55 has a button 74 extending from the upper surface thereof and adapted to contact with the forward end of plate 52 to limit rearward movement of the piston and to assure proper positioning of the Fig. 8 fitting relative to the end of the stop and guide member 40.

When it is desired to force a Fig. 8 fitting into the end of a bar, such bar is properly aligned with the machine and clamped in place in the manner before described. Having a Fig. 8 fitting disposed as shown in Fig. 2, this fitting can be forced into the end of the bar by applying a suitable amount of pressure through a foot treadle (not shown) or any other suitable manner to rotate the bell crank 62 about its pivot and to force the member 56 and associated piston 55 toward the bar. The application of force in a uniform manner causes the Fig. 8 fitting to be forced into the end of the bar without requiring the removal of any material from the bar to accommodate the fitting. Ordinarily, driving of such a fitting into the end of a bar would, on account of the thickness of the fitting, almost invariably cause a splitting of the bar. However, since the end of the bar is firmly clamped by the clamping mechanism, it has been found in actual practice that this type of fitting can be forced into a bar without splitting the same due primarily to the clamping force applied through the cam, which force effectively prevents such splitting during the insertion operation. It has also been found in practice that once the fitting has been introduced in the bar without causing the splitting thereof during the introduction, that the bar, after the clamping pressure has been released, does not split.

The introduction of a fitting of the Fig. 9 type into the end of a bar requires a piston designed to cooperate with this fitting. As shown in Fig. 9, the fitting 80 thereof has two leg portions provided with inward teeth substantially of the same shape and configuration as the Fig. 8 fitting. This fitting, however, instead of being completely flat has the rear part thereof turned upwardly at a 90° angle to the leg portions and this upward extending part has a pin 81 staked or otherwise secured thereto. In conjunction with this fitting, use is made of a piston 55A, one end of which has been illustrated in Figs. 11 and 12 wherein this end of the piston has been shown in conjunction with a Fig. 9 fitting. By reference to these figures, it will be seen that the forward end of the piston 55A has a channel 82 formed in the under surface thereof to accommodate the pin 81.

Piston 55A can be connected to member 56 in the same fashion as the piston 55. When it is desired to force a fitting of the Fig. 9 construction into the end of a wooden bar, such fitting is laid on the guideway in the same manner as the Fig. 8 fitting but with the right angular part at the end thereof extending upwardly. As this fitting is properly positioned in the guideway, the pin 81 is received in the channel 82 so that the upper end part of the piston 55A can bear against the turned up part of the fitting and the edges of the piston 55A can engage the side edge portions of this upturned part. Upon the application of pressure through a foot treadle or other agency in the manner before described, a fitting of this character can be forced into the end of a wooden bar in the manner previously described.

When it is desired to introduce a fitting of the type shown in Fig. 10 into a bar, it is desirable to make use of a still differently shaped piston 55B shown in Figs. 13 to 18 inclusive. The fitting shown in Fig. 10 is of the type known in the art as a gudgeon pin being made up of a nail-like part 90 and a flange 91 extending circumferentially around the pin near the head end thereof. The piston 55B has a longitudinal rib 92 on the under surface thereof which fits in a channel 94 cut in the bottom of the member 40 and extending rearwardly from the depression 50 (Fig. 2). The end of piston 55B is bored out as indicated at 95 to receive the head of a gudgeon pin. This bored out part is so located that only a thin wall is present at the bottom of the rib 92. In addition, a part of the end of the piston is rounded out as at 96 to facilitate inserting a gudgeon pin into the bore 95 from the top of the piston.

Since the gudgeon pin, when assembled in relation to a piston 55B, does not rest on the guideway on which fittings of the other types may rest, a suitable guiding and weight arrangement is provided for insuring that the pin will be forced into a bar in proper alignment with the bore 95. This arrangement is made up of a cross-bar 97 secured to the top of plate 52 and having up-standing spaced plate-like portions 98. Between these plate-like parts 98 is pivotally mounted a dog member 99 having a depending right angular extension 100 which has the end part thereof split or forked as at 101. The space between the forked portions 101 is substantially equal to the diameter of the nail part 90 of a gudgeon pin. A weight block 102 has an opening cut in one edge thereof so that it can fit around the depending part 100 and be pivoted thereto as at 104. When a piston of the type shown in 55 or a piston of 55A types are used, this guiding and weight arrangement can be dispensed with and in that event the parts are folded to the position shown in Figs. 1 and 2. However, when a 55B piston and a gudgeon pin are used cooperatively, use is also made of the guiding and weight arrangement. In Fig. 14, these parts are shown in plan view wherein the gudgeon pin is in cooperative relation to the piston 55B and the various parts of the weight and guiding mechanism are moved into functioning positions. By reference to Fig. 15, it will be seen that the forked end of the depending portion 100 straddles the nail part 90 of the gudgeon pin while the weight 102 rests on the top surface of the member 40. In addition to straddling the gudgeon pin, the forked end of extension 100 contacts with the flange 91 of the pin forcing it into intimate contact with the end of the piston 55B so that the pin is maintained in true horizontal alignment with the piston. As pressure is applied to force the pin into the wooden bar, the parts assume the successive positions shown in Figs. 17 and 18. As the piston moves toward the bar, the forked end part of extension 100 maintains its contact with the flange 91 and continues in a straddled position relative to the part 90 of the gudgeon pin. The member 99, along with its part 100, are rotated slightly about its pivot and at the same time, the weight 102 slides forwardly along the top of member 40, also rotating slightly about its pivot. Thus, this weight serves to prevent the gudgeon pin from moving upwardly out of horizontal alignment while the forked end of the depending member serves to aid in maintaining this designed alignment. As the piston progresses

forwardly, the weight is finally lifted from the member 40 and likewise the forked end of part 100 rides over the top edge of the piston clearing the same, until the parts assume the Fig. 18 position which represents the completion of a stroke forcing the gudgeon pin into the bar.

In Fig. 19, a fragmentary showing of an end of a wooden bar has been illustrated with a fitting of the type shown in Fig. 8 forced thereinto. This result is accomplished by the cooperation of the parts of the machine with a piston of the shape and characteristics described in connection with piston 55. In Fig. 20, a similar showing has been made of a bar having a Fig. 9 fitting introduced thereinto through the cooperation of the machine when equipped with a piston of the type described in connection with piston 55A. In Fig. 21 a similar showing has been made of a bar having a gudgeon pin introduced thereinto by the operation of the machine when equipped with a piston of the type described in connection with the member 55B.

From the foregoing, it will be seen that the present invention provides a machine which operates in a novel and efficient manner to force fittings into the ends of wooden bars in such fashion that the likelihood of splitting the bar has been substantially eliminated. For this purpose, the clamping mechanism described in this specification serves not only to hold a bar in proper position but also serves to apply such compressive force to the bar as to prevent the bar from splitting crosswise thereof. The clamping mechanism is capable of adjustment to compensate for varying thicknesses of bars being operated upon and for this reason, a shim or plate 110 has been shown in Fig. 2 as being positioned on the bed of the machine underneath the clamping plate 17. This plate or shim 110 has a button 111 extending downwardly from the under surface thereof to engage in an opening 112 in the bed of the machine. It is to be understood, of course, that shims of other thicknesses can be used to correspond to the thickness of the bar being processed so that the effective level of the bed can be brought to such a height that a fitting will always be forced into the bar midway between the top and bottom surfaces thereof. To this end, it follows that a thick wooden bar can be proposed without a shim being located on the bed. As the thicknesses of the various bars being processed decreases, shims of increased thicknesses can be interchanged.

The mechanism utilized for forcing a fitting into the bar is simple and efficient in operation and is adaptable to being used in connection with different types of fittings. To this end as previously described, different types of pistons can be interchanged depending upon the particular type of fitting to be forced into a bar.

It is to be understood that while the device has been shown and illustrated as being particularly useful in a hand and foot operated machine, power operation thereof can be accomplished without departing from the scope and spirit of the invention. Accordingly, any limitations imposed upon the invention are to be only those set forth in the following claims.

What I claim is:

1. A machine of the type described, comprising a support for a wooden bar, a stop adjacent said support, yieldable guide means associated with said stop for aligning bars of different widths relative to said stop, means for clamping one end of a bar substantially immovable rela-

tive to said support, and means adjacent said clamping means for forcing a fitting into the clamped end of such bar.

2. A machine of the type described, comprising a support for a wooden bar, means for clamping one end of a bar substantially immovable relative to said support, a stop adjacent said support, yieldable guide means associated with said stop for engagement with one end of a bar and adjustable aligning means for engagement with the other end portion of the bar for aligning bars of different widths relative to said support and said stop, and means adjacent said clamping means for forcing a fitting into the clamped end of such bar.

3. A machine of the type described, comprising a support for a flat wooden bar, a fixed stop to be engaged by one end of the bar, means for clamping one end of a bar substantially immovable relative to said support and against said stop, an open top guideway in the top of said stop for fittings, and means slidable on said guideway and engaging a fitting for moving said fitting along said guideway and for forcing it into the clamped end of such bar.

4. A machine of the type described, comprising a support for a wooden bar, means adjacent said support for forcing a fitting into the end of a wooden bar, and means for clamping a wooden bar relative to said support, said clamping means comprising a plate normally lying over the end of said bar, rotatable cam means for forcing said plate into clamping relation to said bar, a captive handle adjustably secured to said cam means for manipulating the same and means for locking said handle to said cam means in any adjusted position.

5. A machine of the type described, comprising a support for a wooden bar, means adjacent said support for forcing a fitting into the end of a wooden bar, and means for clamping a wooden bar relative to said support, said clamping means comprising a plate normally lying over the end of said bar, a shaft, said shaft carrying rotatable cam means for forcing said plate into clamping relation to said bar, said cam means having as parts thereof wrench engaging surfaces, and a handle having a wrench part captive on said shaft and selectively engaged with said surfaces to vary the angularity of said handle relative to the cam means, and a pivoted locking plate movable into position against the end of said wrench engaging surfaces to lock said handle in adjusted position thereon.

6. A machine of the type described, comprising a support for a flat wooden bar, means for clamping one end of a bar substantially immovable relative to said support, a stop member for said bar adjacent said support, an aligning member slidably mounted and having parts on each side of said stop member, said aligning member having diverging upright flat surfaces normally extending beyond said stop, said aligning member being yieldable longitudinally relative to said stop member to permit a bar to be moved into contact with said stop, said diverging surfaces aligning a bar relative to said stop by contact between the end edges of the bar and said surfaces.

7. A machine of the type described, comprising a support for a wooden bar, means for clamping one end of a bar substantially immovable relative to said support, a stop member for said bar adjacent said support, an aligning member slidably mounted and having parts on each

side of said stop member, said aligning member having diverging upright surfaces normally extending beyond said stop, said aligning member being yieldable to permit a bar to be moved into contact with said stop, said diverging surfaces aligning one end of a bar relative to said stop, and adjustable means for aligning the other end of a bar relative to said stop.

8. A machine of the type described, comprising a support for a wooden bar, means for clamping one end of a bar substantially immovable relative to said support, a stop member for said bar adjacent said support, an aligning member slidably mounted and having parts on each side of said stop member, said aligning member having diverging upright surfaces normally extending beyond said stop, said aligning member being yieldable to permit bars of different widths to be moved selectively into contact with said stop, said diverging surfaces aligning one end of a bar relative to said stop, and adjustable means engaging the other end of a bar and cooperating with said surfaces to align a bar.

9. A machine of the type described, comprising a support for a wooden bar, means for clamping one end of a bar substantially immovable relative to said support, a guideway positioned in axial alignment with a bar clamped in said support, a movable forcing member slidably mounted in said guideway, said movable member having the end thereof recessed to receive one end part of a gudgeon pin, and combined guiding and weight means adapted to engage the other end part of a gudgeon pin to align the same and prevent upward movement thereof while the pin is being forced toward and into a bar, said combined means being contacted by said movable member to progressively move said combined means away from a gudgeon pin as the same is forced into a wooden bar.

10. A machine of the type described, comprising a support for a wooden bar, means for clamping one end of a bar substantially immovable relative to said support, a guideway positioned in axial alignment with a bar clamp in said support, a movable forcing member slidably mounted in said guideway, said movable member having the end thereof recessed to receive one end part of a gudgeon pin having a flange intermediate its ends, guiding means straddling the other end part of a gudgeon pin to force said flange against the forcing member and to align said pin and a weight member resting on

said other end of the pin to prevent upward movement thereof while the pin is being forced toward and into a bar, said guiding means and weight member being contacted by said movable member to progressively move the same away from the gudgeon pin as it is forced into a wooden bar.

11. A machine of the type described, comprising a support for a wooden bar, means adjacent 10 said support for forcing a fitting into the end of a wooden bar, and means for clamping a wooden bar relative to said support, said clamping means comprising a plate normally lying over the end of said bar, rotatable cam means 15 rotatable about a shaft for forcing said plate into clamping relation to said bar, said cam means having an axially extending part provided with wrench engaging surfaces, a handle having one end formed into a box socket type of wrench captive on said shaft, said handle being 20 adjustably engageable with said surfaces to vary the angularity of the handle relative to the cam, and means for locking the handle to the cam in any of the angular positions of the handle.

12. A machine of the type described comprising a support for a flat wooden bar, a fixed stop to be engaged by one end of a bar, means for clamping one end of a bar substantially immovable relative to said support and against said stop, an open top guideway in the top of said stop for fittings and a sliding member movable relative to said guideway, said sliding member having the bottom of one end thereof cut away to fit over and engage a flat fitting resting on 30 said guideway and means for moving said sliding member to cause it to force said fitting into the clamped end of such bar.

13. A machine of the type described comprising a support for a flat wooden bar, a fixed stop 40 to be engaged by one end of a bar, means for clamping one end of a bar substantially immovable relative to said support and against said stop, an open top guideway in the top of said stop for fittings, and a sliding member movable 45 relative to said guideway, said sliding member having the bottom of one end thereof recessed to receive a trunnion extending from an angular part of a flat fitting resting on said guideway, the end of said sliding member engaging said angular part of the fitting and means for moving said sliding member to cause it to force 50 said fitting into the clamped end of such bar.

HANS K. LORENTZEN.
